United States Patent Office

Des. 232,520

Patented Aug. 27, 1974

232,520

BOTTLE

Alan B. Canfield, South Holland, Ill., assignor to
A. J. Canfield, Co., Chicago, Ill.

Filed Aug. 25, 1972, Ser. No. 283,798

Term of patent 14 years

Int. Cl. D9—01

U.S. Cl. D9—96

FIG. 1 is a side elevational view of a bottle embodying my new design; and

FIG. 2 is a top plan view thereof.

I claim:

The ornamental design for a bottle, substantially as shown.
